(57)

CLAIM

The ornamental design for a modular toy component as shown and described.

DESCRIPTION

FIG. 1 is a perspective view of a modular toy component, showing the new design;

FIG. 2 is a bottom end view thereof;

FIG. 3 is a top end view thereof;

FIG. 4 is a right side elevation view thereof;

FIG. 5 is a left side elevation view thereof;

FIG. 6 is a bottom view thereof; and,

FIG. 7 is a top view thereof.

The appearance of any portion of the article between the break lines forms no part of the claimed design.
